METHOD OF COMPLETING WELLS

Abraham J. Teplitz, Oakmont, Pa., assignor to
Gulf Research & Development Company,
Pittsburgh, Pa., a corporation of Delaware

Application May 29, 1945, Serial No. 596,511

2 Claims. (Cl. 166—22)

1

This invention pertains to an improved method of completing an oil well for satisfactory production by making use of a radioactive tracer material. It is particularly applicable in cases where pipe is set through the producing zone and then perforated for production.

In completing an oil well prior to placing it on production, it is highly desirable to guard against the possibility of producing undesirable components, particularly water and sometimes gas. The early methods of completion consisted essentially of setting casing above the producing formation and allowing the oil to flow into the well from the open formation. This obviously permitted water, gas and oil to enter the well more or less indiscriminately and the production of water or gas was difficult to control.

In more modern completion practice the casing does not stop above the producing zone but is set through it. Cement is forced around the bottom of the casing and into the annular space between the casing and the formation. An attempt is made to force the cement into the annular space all along the producing zone. The casing (and cement) is then perforated by means of a gun perforator at the proper levels so as to permit production from only desirable oil formations. In this way the production of gas and water is to a large extent avoided. This technique is now being widely used.

In some parts of the United States, particularly along the Gulf Coast where many of the deeper sediments are relatively unconsolidated, some difficulties have been encountered in completing wells by this latest technique. It is found in many cases that after the pipe is cemented and perforated for production, extraneous fluids such as water and gas still flow into the well along with the oil. This usually results from channels or crevices in the cement behind the pipe, which permit communication with water or gas formations from which production is undesirable. The channels in the cement may be tortuous passages either between the casing and the cement or between cement and formation or through the body of the cement itself. In any case, these channels form passages which permit unwanted movement of fluid longitudinally along the hole behind the casing from one formation to another.

The wide prevalence of such channels in casing cementations has only recently been recognized and no satisfactory method of combating the condition has previously been devised. In present practice when the initial production test yields water or an excess of gas along with oil, thus

2

revealing the existence of serious imperfections in the cementing, no attempt is made to determine the positions of the troublesome channels. The procedure heretofore used to correct this condition is to squeeze more cement into the perforations at high pressure, and then to re-perforate the pipe in the original interval hoping that channels have been closed by the squeeze job. An alternative procedure sometimes employed is to make a guess, aided by an electrical log or core log of the well, as to the possible source of contamination that is whether it is above or below the producing formation, and then to perforate the pipe between these sources and the original perforations, after which cement is squeezed into all perforations and the original zone is re-perforated for production. Often as many as four or five squeeze cement operations are performed before the water and gas are successfully sealed off, and instances are known where as many as ten such squeezes have been necessary. In addition to being costly in time and equipment, the practice of squeezing cement at high pressure directly against a producing formation sometimes damages the formation so that its productive capacity is reduced or even destroyed.

In this invention I provide a method of definitely determining the source of undesirable fluids so that any perforation and cement squeeze operations may be made intelligently and with utmost effectiveness. At the same time the method avoids contact of the cement with the producing formation, thus avoiding any chance of damaging the well.

35 It is an object of this invention to provide a positive method of determining which portion of the cement is defective in that it contains channels or crevices.

40 A further object of this invention is to provide a method of locating defective regions of cement in the annular space behind a well casing so that these regions may be recemented and sealed.

45 Another object of this invention is to provide a method of positively determining the source of undesirable fluid so that this source may be cemented and sealed off.

Another object of this invention is to provide a method of completing or re-completing a well so as to effectively exclude undesirable fluids.

50 A still further object of this invention is to provide a method of locating behind the casing such channels which permit undesirable fluids to enter the well through perforations opposite desirable producing formations so as to permit

squeezing of cement into these channels in order to seal them.

Another object of this invention is to provide a method of determining defective portions of cement behind a well casing so as to permit squeezing fresh cement directly into the region where it is needed, thus avoiding injury to the producing formation and expediting the completion of the well.

These objects are accomplished by the method of this invention in the following manner. Its application is illustrated by way of example in the appended drawings of a well which is producing oil and excess gas and little water from perforations in pipe which is cemented through the active producing zone. Reference may be made to the drawings in which:

Fig. 1 shows a cross section of a well to which my invention may be applied;

Fig. 2 shows a cross section of a well after the application of radioactive mud according to my invention;

Fig. 3 shows a graph of a preliminary well log taken in the practice of my invention;

Fig. 4 shows a cross section of the well of Fig. 2 after flowing for a brief period;

Fig. 5 shows a graph of a well log taken after the brief period of flow, and

Fig. 6 shows a cross section of a well completed according to my invention.

Referring to Fig. 1, numeral 10 shows a bore hole in which the conventional final casing string 11 extends to the bottom of the well, penetrating formations 12, 13, 14 and 15. The section extending through formation 12 to 15 is the producing zone and the casing is cemented at 16 throughout the length of this producing section. Opposite the oil-bearing horizon 14 the casing and cement have been perforated in conventional manner, such perforations being shown at 17. The cement around the casing is assumed to completely fill the space between the casing and the formation wall. However, imperfections 18 and 19 may be present and are originally not known to exist. Following a production test, which for purposes of illustration in this well may show oil with considerable undesirable excess gas and a small amount of undesirable water, it is deemed necessary to correct this faulty condition.

As a first step in the practice of my invention, I locate opposite the producing section a quantity of drilling mud or bentonite suspension containing a suspended radioactive tracer material. Such radioactive tracer may be finely ground carnotite, for instance, or any other insoluble natural or artificial radioactive compound. A 5% aqueous bentonite suspension containing about one pound of finely ground carnotite per barrel may be used. Since carnotite ores vary considerably in radioactive strength, it is desirable to select for the purpose of practicing this invention, one of the commercial carnotite ores containing about ten to twenty milligrams of radium per ton. Pressure is applied to this mud in conventional manner, either by use of a conventional packer or squeezing tool, and the mud is forced through the perforations into any space which may exist behind the casing.

Fig. 2 shows the radioactive mud 20 penetrating the perforations 17 and the channel defects 18 and 19. Sufficient pressure is applied to force the radioactive mud into these openings or channels, but due to the nature of the drilling mud suspension, the suspended matter is not forced into the formation itself. The pump pressure ap-

plied at the surface is maintained at a value just sufficient to cause the suspension to move through the perforations and should not be permitted to rise to high values commonly used in squeezing operations. When the pressure begins to climb rapidly showing that the movement of the radioactive suspension has practically ceased, pressure is released and excess mud is circulated out of the well. Thus in Fig. 2, the well may be filled with non-radioactive mud or fluid, leaving radioactive mud 20 only in the openings 17, 18 and 19.

Upon removal of the excess mud, a radioactive logging instrument 21 is lowered into the well on cable 22. Such instruments are well known in the art and do not form the subject matter of this invention. As the indicator 21 is lowered through the producing section, a radioactivity log is made, an example of which is illustrated in Fig. 3. This log is of a conventional type, being a graph 31 showing depth markings 30 indicating the position of the detector 21 and a curve 24 which indicates the degree of radioactivity observed with reference to an arbitrary zero line 23. Thus survey will reveal the position of the carnotite suspension which has entered any passages behind the pipe by pushing back into the formations any fluid which was produced into these channels. As illustrated in Fig. 2, the radioactive mud has penetrated a channel defect 18 leading from producing formation 14 to formation 12 which for example may contain gas, and also into channel defect 19 leading from producing formation 14 to formation 15 which for example may contain water. This radioactive mud is shown on the curve by the two regions of high intensity at 26 and 27 opposite the defects. The depth at which perforations 17 were made is known and may be marked on the graph at the proper points 33 for purposes of reference.

The well is now permitted to produce for a short time so as to permit it to clean out the radioactive mud which has been forced into flowing channels.

Fig. 4 illustrates the condition of the well after such a period of flushing. The well is produced for a time sufficient to allow the undesirable constituent to enter the casing thus cleaning the mud out of the channel through which it flows. Thus Fig. 4 illustrates the radioactive mud flushed out of defect 18 by the gas coming from formation 12. Partial removal of radioactive mud from defect 19 by a flow of oil from formation 14 and possibly a slight flow of water from formation 15 is also illustrated. These facts are determined from a subsequent radioactivity log as follows.

After the above period of flowing to flush the radioactive mud from channels another radioactivity log is again run. Such a second log is illustrated in Fig. 5. For comparison, the log of Fig. 3 is superimposed as a broken line on Fig. 5. It will be noted that the high intensity indication of point 26 (Fig. 3) does not appear on the second log, Fig. 5; whereas, the high intensity indication at 27 (Fig. 3) has decreased only slightly. This indicates that the foreign fluid has been produced from the formation 12 and, in fact, one may conclude that its source is opposite the point of farthest extremity 28 from the producing perforations 17 where previously indicated radioactive mud has been removed by the flowing process.

The well is now perforated opposite the point 28 indicated to be the source of the undesirable fluid. Such new perforations are shown at 29 in Figure 6. A packer 32 is inserted between this point and the original perforations 17 and cement squeezed into the perforations 29. This cement, shown in Fig. 6 at 34, will effectively seal the source of undesirable fluid without in any way damaging the face of the producing formation 14. The lower portion of channel 19, indicated by the region of high radioactivity at 27, Figs. 3 and 5, is not contributing to the output of the well, since the radioactive logs show that the mud is not completely flushed out. If, at a later date, water production becomes excessive, its source may be determined by repeating the method of this invention.

Although the channel 18 communicates with the producing formation, the pressure developed against the producing formation during the squeeze will be relatively small since in most cases the cement will bridge somewhere in the channel. If it is felt necessary, a small amount of cement may be squeezed in and allowed to harden before squeezing the main portion of the cement. This precaution will entirely eliminate any danger of damaging the producing sand. Subsequently the packer 32 may be removed, either by collapsing it if a removable type, or by drilling it if it is a drillable type.

My invention may also be applied to a pumping well in a similar way as applied to a flowing well. In this case the step of flushing radioactive mud from channels producing undesirable fluid must be accomplished by pumping or bailing.

In some instances it may be desirable to use an oil base fluid instead of the aqueous radioactive fluid. A suspension of carnotite in oil containing a thickening agent may be employed in such cases.

While I have described my invention in the case of a well producing oil with considerable undesirable excess gas and a small amount of undesirable water, this is for purposes of illustration and not a limitation. My method may be used 45 with equal effectiveness on any type of well in

which it is desired to ascertain the source of undesirable components and avoid their production. What I claim as my invention is:

1. A method of completing a well which is cased and cemented throughout the producing section said casing and cement being perforated in the zone of desirable production, comprising forcing drilling mud containing radioactive material in suspension into the producing perforations, 10 removing excess drilling mud, running a radioactivity log of the producing section, allowing the well to produce for a short interval, running a second radioactivity log to determine the presence of channels permitting entrance of undesirable components, and perforating and re-cementing opposite the indicated source of such undesirable fluids.
2. A method of completing a well which is cased and cemented throughout the producing section said casing and cement being perforated in the zone of desirable production comprising forcing a suspension of radioactive material into the producing perforations and cement channels, removing the suspension from inside the casing, 20 running a radioactivity log of the producing section, allowing the well to produce for a short interval, running a second radioactivity log to determine the presence of channels which permit entrance of undesirable components, perforating and re-cementing opposite the indicated source of such undesirable fluids and erecting a barrier inside the casing between said perforations and the original perforations whereby the zone of production and original perforations are 25 protected from contact with the cement during such re-cementing operation.
